UNITED STATES PATENT OFFICE.

EUGENE C. AMSDEN, OF BOSTON, MASSACHUSETTS, ASSIGNOR TO AMSDEN & BARNARD, INC., OF BOSTON, MASSACHUSETTS, A CORPORATION OF MASSACHUSETTS.

METHOD OF MAKING FURNITURE STANDARDS AND THE LIKE.

Application filed January 19, 1927. Serial No. 162,194.

This invention relates to methods of manufacturing standards of the general type used in school furniture, opera chairs, settees, and the like.

Standards of this character usually include legs which terminate in feet that are spread apart for a considerable distance in order to give the standard the desired stability. If the legs and body portion of such a standard are made of integral construction and from sheet metal, the stock from which the blank is cut must, according to the usual processes, be at least as wide as the extreme distance between the feet. The usual methods of manufacturing such standards therefore involve the formation of a very substantial amount of scrap and this, in turn, increases the expense of manufacture of the standards. The present invention deals with this problem, and it aims to improve the methods of manufacturing such standards with a view to economizing material, while at the same time providing a strong, rigid and entirely satisfactory product. It is an especially important object of the invention to devise a method of manufacturing standards from strip stock much narrower than the distance between the feet of the finished standard.

The nature of the invention will be readily understood from the following description when read in connection with the accompanying drawings, and the novel features will be particularly pointed out in the appended claims.

In a prior application I have disclosed a novel construction of school desk standard and a method of making it. For convenience the present invention will be herein disclosed in connection with the manufacture of the standard shown in my earlier application, it being understood that the invention is in no wise limited to the manufacture of the standard shown.

In the drawings,

Figure 1 is a perspective view of a school desk including standards constructed in accordance with this invention;

Fig. 1^a is a cross-sectional view on the line $\alpha-\alpha$, Fig. 1;

Fig. 2 is a plan view showing a blank for a school desk standard and a method of cutting this blank from strip stock;

Fig. 3 is a perspective view of a sheet metal blank for a school desk standard;

Figs. 4 and 5 and 6 are perspective views showing successive steps in the manufacture of a standard according to this invention;

Figs. 7 and 8 are plan views partly in cross-section, showing steps in the method of forming the feet;

Figs. 9, 10 and 11 are cross-sectional views illustrating additional steps in this method;

Fig. 12 is a plan view, partly in cross-section, showing a finished foot;

Fig. 13 is a similar view showing a slightly different foot construction; and

Figs. 14 and 15 are perspective views showing a somewhat different method of making a desk standard from the blank shown in Fig. 3.

Referring first to Fig. 1, the desk there shown comprises a desk top or box 2 of a common construction supported on standards which, in this instance, are adjustable. Each of these standards comprises an upper unit 3 and a lower unit 4, the upper unit having grooves 4 to receive tongues 5—5 and lugs 6—6 which are integral with and form part of the body portion of the lower unit of the standard. A bolt 7 projects through a hole 8 in the part 4 and also through a slot 9 in the part 3 and adjustably secures these two parts together.

In this particular construction the edge flanges 10—10 of the legs are provided with inturned margins 12 which give added stiffness and rigidity to the legs. In some constructions, however, these inturned margins 12—12 are omitted, and the method provided by this invention will be described in connection with Figs. 2 to 6, inclusive, as applied to the manufacture of a standard which does not include the marginal flanges 12—12.

Referring to Fig. 2 it will be observed that the blanks for the standards are cut out of a strip S of flat sheet metal of suitable thickness and of a width substantially equal to that of the body portion of the standard. The cutting of the blanks may conveniently be performed with a die of the shape shown at 13, Fig. 2, this die being adapted to sever the strip S into suitable lengths for the individual blanks, and at the same time to divide each length for a substantial distance to form legs. Each blank so formed, therefore, has a body portion 4' and two legs 14—14 extending side by side from one end of said body portion. The cutting off operation preferably shapes the upper end of

the body portion 4', forming the lugs 5 above referred to. A complete blank is shown in Fig. 3.

The legs 14-14 are next bent out of the plane of the body portion of the blank as shown in Fig. 4. In this same operation or in independent operations, if desired, flanges *a-a* are formed along the inner margins of the legs and the ends of the legs are pressed, as shown at *b*, to form feet.

The opposite edges of the body portion 4' of the blank are next bent upwardly into positions approximately at right angles to the plane of said body portion of the blank thus forming the flanges *d-d*, Fig. 5. This bending operation takes place substantially along the lines *c-c*, Fig. 4, which are approximately continuations of the inner edges of the flanges *a-a*. Consequently, this operation results in rotating the free ends of the legs, that is, the ends opposite the body 4', away from each other and spreading them apart. This spreading of the end of one leg away from the other takes place due to the fact that the end of the leg is offset for a considerable distance from the axis on which the bending or rotative movement occurs. The bending operation preferably is stopped when the flanges *a-a* are brought substantially into the plane of the body portion 4' as shown in Fig. 5, of the blank, where said flanges form the main portions of the legs, and the outer margins of the legs form continuations of the flanges *d-d* at the opposite edges of the body 4'.

It will be observed that the distance which the feet *b-b* are spread apart will depend upon the degree of curvature or amount of offset given to the legs 14-14 at the stage 40 of manufacture shown in Fig. 4. Also, that if one of these legs is bent initially farther out of the plane of the body portion of the blank than the other leg, then the end of the former will be spread farther away from the center line of the blank than the latter when the legs have been rotated about the axes *c-c* as above described.

In order to increase the stiffness and rigidity of the legs, their inner margins preferably are pressed into a slightly offset relationship, as shown at 15-15, Fig. 6, this offset running up into the body portion 4' of the standard. At the same operation the lugs 6-6, Fig. 6, may be formed. The lugs 5 may also be turned up at this time, or more preferably at the same time that the flanges *d-d* are formed.

The foot trimming and shaping operations are illustrated in Figs. 7 to 12, inclusive, the roughly shaped foot being first trimmed to the desired outline, as shown in Fig. 8, and then pressed to form the marginal flange 16 and the screw head sockets 17, as shown in Fig. 10. Figs. 11 and 12 shows the foot 65 after it has been finally shaped and the holes

punched through the bottoms of the sockets to receive the screws.

Instead of making the leg 14 with a comparatively sharp or abrupt angle, it may be so shaped as to have a smoother and more gradual curve, and such a construction is shown at 14' in Fig. 13.

The standard above described in connection with Figs. 3 to 6, inclusive, does not have the inturned marginal flange 12 of the standard shown in Figs. 1 and 1^a, although such a flange obviously could be formed along the edges of the legs of the standard shown in Fig. 6, if desired. Where such a flange is to be made, I prefer to adopt the process shown in Figs. 14 and 15.

Starting with the blank shown in Fig. 3, the legs of the blank are first curved out of the plane of the blank, as shown in Fig. 14, and either during this step, or at an independent operation, flanges *e* are formed along the inner edges of the legs and flanges 12 along the outer edges. These flanges continue through the body portion 4' of the blank, forming channels in the opposite margins of said part. The channelled sections of the body portion 4' are next bent upwardly and toward each other, as indicated by the arrows in Fig. 14, thus rotating the two legs about the lines *f-f* as axes and thereby swinging them apart. This movement separates the ends of the legs in the manner previously described and takes the central channel section out of the body portion of the blank.

In fact, this bending of the body portion with the simultaneous rotation of the legs, can be produced simply by pressing the entire raised central portion of the part 4' downwardly and flattening it out, as shown in Fig. 15. In this method, also, as in the process above described, the amount of spread given to the legs will depend upon the degree of curvature imparted to them in the step illustrated in Fig. 14. The bending or rotative movement is stopped when the inside flanges *e-e* are brought into the plane of the body portion of the blank where they form continuations of said portion, and the portions of the legs between the flanges *e* and 12 then form the edge flanges 10 of the legs as shown in Figs. 1 and 1^a. It should be noted that the process illustrated in Figs. 14 and 15 can be used to equal advantage in producing the standard shown in Fig. 5 and which does not have the flanges 12-12.

The partly shaped standard shown in Fig. 15 may next have the marginal offsets 15 and the lugs 6 pressed into it as shown in Fig. 5, and the feet may then be shaped as above described.

It will now be understood that this invention provides a method of making standards of the character described, which is very simple and is far more economical of stock 124

than the prior processes, the maximum width of stock required being only that necessary for the body portion of the standard. All of the bending operations can be performed cold, that is, while the metal is at ordinary atmospheric temperatures. The metal is so disposed that a strong rigid standard of pleasing appearance is produced.

The construction of the dies required for performing the various operations above described will be obvious to those skilled in the pressed metal industry, and no description or illustration of them is necessary here. Obviously the design of the dies and the mechanisms used for operating them will depend to some extent upon the nature of the equipment available, the size of the presses, and the like. The order of the steps of the process also will depend to some extent upon these considerations, certain steps being combined in some cases where it would not be desirable or economical to combine them in others. The invention therefore is not limited to the precise order of steps above described.

Furthermore, while I consider it preferable to cut the blanks out of narrow strip stock, the blanks can be died out of wide sheet stock if desired, the invention effecting nearly as great a saving in stock where this practice is followed since the blank required may be much narrower than in prior processes. While, therefore, preferred methods of practicing the invention have been above described, it will be understood that considerable variation is permissible in the steps and their order of performance while still retaining the essential features of the invention.

Having thus described my invention, what I desire to claim as new is:

1. That improvement in processes of making standards for furniture and the like, which consists in providing a sheet metal blank having two legs lying side by side, bending one of said legs out of the plane of said blank, flanging the latter leg, then bending the flanged leg into an angular relationship to the plane of the blank, and during the latter bending operation rotating the free end of said flanged leg outwardly and away from the opposite leg.

2. That improvement in processes of making standards for furniture and the like, which consists in providing a sheet metal blank having two legs lying side by side, bending one of said legs out of the plane of said blank, forming a flange along one side of the latter leg, then bending the opposite side of said flanged leg near the body of the blank into an angular relationship to the plane of said body, and thereby rotating the free end of said flanged leg outwardly and away from the opposite leg.

3. That improvement in processes of mak-

ing standards for furniture and the like, which consists in providing a sheet metal blank having two legs lying side by side, bending one of said legs out of the plane of said blank, shaping the latter leg to provide a flange extending longitudinally thereof, and then rotating said flanged leg in a direction to swing its free end away from the other leg.

4. That improvement in processes of making standards for furniture and the like, which consists in providing a sheet metal blank having two legs lying side by side, bending one of said legs out of the plane of said blank, forming a flange along one side of the latter leg adjacent to its free end, and then rotating the free end of the leg so flanged about an axis extending longitudinally of the portion of said leg adjacent to the body of the blank to swing said free end away from the opposite leg.

5. That improvement in processes of making standards for furniture and the like, which consists in providing a sheet metal blank having two legs lying side by side, bending one of said legs out of the plane of said blank, shaping the latter leg to provide a flange extending longitudinally thereof, then rotating the free end of said flanged leg about an axis extending substantially along one edge of the portion of said flange adjacent to the body of the blank, and thereby by swinging the free end of said bent leg away from the opposite leg.

6. That improvement in processes of making standards for furniture and the like, which consists in providing a sheet metal blank having two legs lying side by side, bending one of said legs out of the plane of said blank, forming a flange along one side of said bent leg, and then bending said blank to bring said flange substantially into the plane of the body portion of the blank.

7. That improvement in processes of making standards for furniture and the like, which consists in providing a sheet metal blank having two legs lying side by side, bending one of said legs out of the plane of said blank, shaping the latter leg to provide a flange extending longitudinally thereof, then rotating the free end of said flanged leg about an axis extending substantially along one edge of the portion of said flange adjacent to the body of the blank, until said flange is brought substantially into the plane of the body portion of the blank, and thereby by swinging the free end of said bent leg away from the opposite leg.

8. That improvement in processes of making standards for furniture and the like, which consists in providing a sheet metal blank having two legs lying side by side, bending one of said legs out of the plane of said blank, forming a flange along the inner side of said bent leg, and then bending

the body portion of said blank in a direction to swing the free end of said bent leg away from the opposite leg.

9. That improvement in processes of making standards for furniture and the like, which consists in providing a sheet metal blank having two legs lying side by side, bending one of said legs out of the plane of said blank, forming a flange along the inner side of said bent leg, and then bending said blank to bring the portion of said bent leg adjoining said flange into approximately a right angle relationship to the plane of the body portion of said blank.
10. That improvement in processes of making standards for furniture and the like, which consists in providing a sheet metal blank having two legs lying side by side, bending one of said legs out of the plane of said blank, forming a flange along the inner side of said bent leg, and then bending the body portion of said blank about an axis forming substantially a continuation of one edge of said flange and thereby forming a flange on said body portion and also swinging the free end of said bent leg away from the opposite leg.
11. That improvement in processes of making standards for furniture and the like, which consists in providing a sheet metal

blank having two legs lying side by side, bending said legs out of the plane of the body portion of said blank, forming a flange along the inner edge of each leg, and then bending the body portion of the blank to swing the free ends of said legs away from each other.

12. That improvement in processes of making standards for furniture and the like, which consists in providing a sheet metal blank having two legs lying side by side, bending one of said legs out of the plane of said blank, forming flanges along the opposite edges of said bent leg, and then bending said blank in a direction to swing the free end of said bent leg away from the opposite leg.

13. That improvement in processes of making standards for furniture and the like, which consists in providing a sheet metal blank having two legs lying side by side, bending said legs out of the plane of the body portion of the blank, forming flanges along both edges of each of said legs and continuing said flanges into the body portion of the blank, and then bending the body portion of the blank to swing the free ends of said legs away from each other.

EUGENE C. AMSDEN.
